JOSEPH BIRON, OF MAILLARDVILLE, BRITISH COLUMBIA, CANADA

WINDOW-SASH ADJUSTER

Application filed April 13, 1929. Serial No. 354,905.

My invention relates to improvements in window sash adjusters the objects of which are to provide means whereby the one sash of a window may be used to counterbalance another, so that the use of a box frame fitted with weight pockets are avoided and considerable economy in building construction is effected. Further objects are to provide means whereby either of the sashes of a window may be set in adjusted open position at will, and if desired by raising the lower sash a corresponding lowering of the upper sash may be effected or vice versa.

The invention consists essentially of a pair of cables or cords each having one end secured to one sash and adjustably secured to the other at the other end, which sash cables are adapted to run over pulleys attached to the head of the window frame, as will be more fully described in the following specification, and shown in the accompanying drawings in which:—

Fig. 1 is a fragmentary general view of the invention.

Fig. 2 is a perspective view of the left hand fastening member attached to the stile of the lower sash.

Fig. 3 is a cross section taken on the line 3—3 of Fig. 2.

In the drawings like characters of reference indicate corresponding parts in each figure.

The numeral 1 indicates generally a window frame having so-called pulley stiles 2 and a head 3. Between the pulley stiles 2 are slidably fitted a lower and an upper sash numbered 4 and 5 respectively. The sashes are formed in the usual manner with stiles 6 and meeting rails 7 and the upper sash 5 is fitted with a top rail 8.

Secured adjacent each end of the head 3 of the frame 1 is a pulley 9 over which a cord or light cable 10 is adapted to run, one end of each cable is secured by a fastening plate 11 to a stile 6 of the upper sash 5 and the other end of the cable it attached to the upper end of a slide generally indicated by the numeral 12 as at 13 see particularly Figure 2. The slide 12 consists of a pair of spaced plates 14 and 15, the former being of

greater width than the latter, the purpose of which will hereinafter appear.

The plates 14 and 15 are held in spaced relation by an upper and a lower pin respectively numbered 16 and 17, the pin 16 forming an anchorage for one end of the cable 10 and the pin 17 forming a pivot upon which a sidewise rocking pawl 18 having a lower hooked member 19 is fulcrumed. A pair of guides 20 are fitted on the face of the stiles 6 each of which consists of a back plate 21, see Figure 2, fitted with opposed side rails 22 and 23.

The rails 22 and 23 are so mounted as to provide a pair of vertical grooves 24 which are adapted to receive the edges of the plate 14 of the slide to hold it in place and to permit of its free vertical movement along the guides 20. A plurality of sawtooth recesses 25 are formed in the face of the rail 23 which are capable of receiving the pawl 18 and holding the slide against upward movement when so engaged. The guides 20 will preferably be formed in pairs one with the sawtooth recesses on one side and one with said recesses on the opposite side so that a person on pulling both sides downwards by the hooked members 19 of the pawls 18 will tend to incline said pawls to engage their respective recesses.

Having thus described the several parts of my invention I will now briefly explain its operation.

When it is desired to open the upper window the hook members 19 are moved sideways to disengage the recesses 25 and to permit the slides 12 to move upwards along the guides 20 and the top sash to descend to the desired opening when the pawls are permitted to engage the recesses to lock the slides in adjusted position. Should the opening be desired at both top and bottom of the window the lower sash is then raised and through the cords 10 the top sash still further lowered.

If it is desired to open the lower sash only, it is raised in the usual way and the hooked members 19 are drawn downwards along the guides 20 until the cables 10 are taut when

the rocking of the pawls 18 locks the slide 12 and leaves the sash in adjusted position.

What I claim as my invention is:

In window sash adjuster, a guide adapted for attachment to a sash and fitted with recesses, a slide adapted to be anchored remote from said sash, said slide having a pawl, and hand operated means for rocking the pawl to engage one of the recesses of the guide to lock the slide to adjusted position.

10 Dated at Vancouver, B. C., this 4th day of April, 1929.

JOSEPH BIRON.
